UNITED STATES PATENT OFFICE

138,263

DESIGN FOR AN EMBOSSED LEATHER

Leonard I. Freedman, New York, N. Y.

Application January 26, 1944, Serial No. 112,335

Term of patent 7 years

(Cl. D87—3)

To all whom it may concern:

Be it known that I, Leonard I. Freedman, a citizen of the United States of America, residing in New York city, county of New York, and State of New York, have invented a new, original, and ornamental Design for an Embossed Leather, of which the following is a specification, reference being had to the accompanying drawings, forming part thereof.

Fig. 1 on the drawings is a plan view of an embossed leather showing my new design.

Fig. 2 is a detailed view on an enlarged scale of a portion of the leather shown in Fig. 1.

Two design units are contained between the dot and dash lines, which unit is repeated in regular succession as indicated by the extensions beyond the unit boundaries.

I claim:

The ornamental design for an embossed leather, substantially as shown and described.

LEONARD I. FREEDMAN.
